UNITED STATES PATENT OFFICE

SILVIO DRUDI, OF ALLENTOWN, PENNSYLVANIA

RAILROAD SAFETY DEVICE

Application filed October 8, 1930. Serial No. 487,324.

This invention relates to a railroad safety device and has for one of its important objects to provide, in a manner as hereinafter set forth, an apparatus embodying a novel construction and arrangement of parts through the medium of which the whistle on a locomotive which seems to be traveling over a track equipped with a portion of this invention will be automatically sounded for the purpose of warning the engineer or other operator of the locomotive that there is danger in the vicinity and to bring the locomotive to a stop.

Another important object of the invention is to provide a railroad safety device embodying coacting means on the track and locomotives which are traveling over the track for sounding the whistle when a locomotive may be traveling in the wrong direction on the track for preventing head-on collisions.

Other objects of the invention are to provide a railroad safety device of the character set forth which will be simple in construction, strong, durable, efficient in operation and which may be manufactured and installed at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is an elevational view of a portion of the apparatus which is mounted on the locomotive.

Figure 2 is a view in side elevation of the apparatus which is mounted on the locomotive.

Figure 3 is a detail view in end elevation of the supporting frame which is mounted on the roof in the locomotive cab and showing the pivotally mounted, spring operated latch plate which retains the whistle operating lever in inoperative position.

Figure 4 is a fragmentary horizontal sectional view taken substantially on the line

4—4 of Figure 2 looking in the direction indicated by the arrows.

Figure 5 is a sectional view taken substantially on the line 5—5 of Figure 11 looking in the direction indicated by the arrows and showing a portion of the mechanism which is mounted on the track between the rails.

Figure 6 is a detail view in end elevation of the whistle operating tripper unit which is mounted on the track.

Figure 7 is a detail end elevation of the train actuated unit illustrated in Figure 5 which operates the unit illustrated in Figure 6.

Figure 8 is a view in side elevation of the tripper unit which actuates the locomotive whistle.

Figure 9 is a view in side elevation of the train operated unit illustrated in Figures 5 and 7, looking at said unit from the opposite side from which Figure 5 is viewed.

Figure 10 is a fragmentary view in elevation of the lower portion of the train carried apparatus illustrated in Figure 1 and showing the side thereof which is opposite the side shown in Figure 2 of the drawings.

Figure 11 is a view in top plan of the whistle actuating tripper unit and the unit which sets the whistle operating unit.

Figure 12 is a detail view in cross section taken substantially on the line 12—12 of Figure 11 looking in the direction indicated by the arrows.

Figure 13 is a detail view in horizontal section taken substantially on the line 13—13 of Figure 1.

Figure 14 is a diagrammatic view showing the track apparatus in operative position.

Referring to the drawings in detail and to Figures 1 to 4, thereof in particular, it will be seen that the reference numeral 1 designates generally a supporting frame or structure which is adapted to be mounted in vertical position transversely beneath the cab of a railroad locomotive at the rear end portion thereof, the supporting structure or frame being mounted in any suitable manner at the most convenient point on the locomotive cab. The supporting structure or frame 1 includes the vertical end bars 3 and 4 be-

tween which extend an upper pair of cross bars 5, a lower pair of cross bars 6 and an intermediate pair of cross bars 7. The bars of each of the pairs 5, 6 and 7 are secured in any suitable manner, as by welding, to the vertical edges of the end bars 3 and 4 in a manner to dispose the bars of each of the pairs in spaced, parallel, opposed relation to each other.

10 A pair of horizontally disposed flat metallic plates of the configuration best illustrated in Fig. 13 of the drawings are disposed for sliding movement on the upper and lower edges of the pair of cross bars 6, said plates being designated by the reference numeral 8 and being further provided with a connecting block 9 which is slidably disposed between the cross bars 6. A substantially triangular striker plate 10 is rigidly fixed to the lowermost plate 8 and depends therefrom. A pair of flat, horizontally disposed metallic plates 11 of a shape similar to the plates 8 are slidably engaged with the upper and lower edges of the intermediate cross bars 7 and are connected together by a block 12 which is slidably disposed between the bars 7. A stem 13 extends through the plates 11 and the block 12 and has threaded on its upper end the retaining nut 14. The stem 13 depends from the lowermost of the plates 11 and has its lower end portion apertured to slidably receive the bight portion of an upstanding yoke 15 which is rigidly mounted on the uppermost plate 8. A set screw 16 is threaded into the lower end of the stem 13 for frictional engagement with the yoke 15 for securing said yoke and the stem in adjusted position relative to each other. The stem 13 has its intermediate portion provided with 20 transverse threaded passage for threadedly receiving the screw shaft 17 which is journaled in the end bars 3 and 4 of the supporting structure or frame 1. The screw shaft 17 projects beyond the end bar 3 and has fixed 25 on said projecting end portion a beveled gear 18 which meshes with a beveled gear 19 fixed on the lower end portion of a vertical shaft 20 which is journaled in the brackets 21 and 22 which extend laterally from the end bar 3. The vertical shaft 20 is rotatable upwardly 30 through the floor of the locomotive cab (not shown) and has fixed on its upper end the operating wheel 23.

35 A pair of upstanding metallic straps are secured to the inner sides of the lower end portions of the vertical end bars 3 and 4 immediately above the cross bars 6, said straps being designated by the reference numeral 24 and having rigidly connected to their upper end portions the horizontally disposed right angularly extending arms 25 upon the free end portions of which are pivotally mounted the metallic plates 26. The plates 26 have their intermediate portions connected 40 to the inner sides of the arms 25 for swing-

ing movement in a vertical plane. Spaced, parallel rods 27 extend between the end portions of the plates 26 and are rigidly secured to said plates. Struts 28 extend between intermediate portions of the rods 27 for bracing said rods. A vertical finger 29 has its upper portion provided with spaced eyes through which the rods 27 pass in a manner to rigidly mount the finger 29 in position on said rods. An arm 30 extends upwardly from the rods 27 and has its upper end portion operatively connected with the lower end portion of a lever 31 through the medium of the link 32. A supporting bracket 33 is mounted on one of the intermediate cross bars 7 and has its free end portion pivotally connected to an intermediate portion of the lever 31 as indicated at 34 in Figure 2 of the drawings. A bracket 35 is mounted horizontally on one of the upper cross bars 5 above the bracket 33 and has journaled therein a pulley wheel 36.

50 A polygonal, metallic skeleton frame 37 is provided with apertured ears 38 for rigidly suspending said frame in vertical position from the roof of a locomotive cab and mounted for swinging movement on opposite sides of the frame 37 adjacent one end thereof is a pair of bars 39 which have their free ends connected together by a weight 40. Swinging movement of the bars 39 in one direction is limited by the out-turned flanges 41 formed integrally on the flat metallic plates 42 which are secured by any suitable means such as screws 43 to the frame 37. An apertured metallic plate 44 is rigidly mounted on the end of the frame 37 which is remote from the plates 42. A rod 45 has one end pivotally connected, at 46, to intermediate portions of the bars 39 and the rod 45 projects slidably through the aperture in the plate 44 and has formed therein adjacent its pivoted end a notch for engagement with the wall of the aperture in the plate 44 for releasably retaining the bars 39 in inoperative position and against swinging movement under the impulse of a coil spring 47 which encircles the rod 45 and yieldingly urges the bars 39 in a direction away from the plate 44 and toward the flanges 41. As best seen in Figure 3, a lever 48 has one end pivotally connected to the frame 37 as at 49, said lever 48 being provided with a slot through which the rod 45 extends. The free end portion of the lever 48 has mounted thereon an eye 50 to which one end of a flexible chain 51 is connected, said chain 51 being trained over the pulley wheel 36 and having its other end connected to the upper end of the lever 31. The chain 51 is adapted to swing the lever 48 in one direction in a manner to disengage the notch in the rod 45 from the wall of the aperture in the plate 44 and permit the coil spring 47 to swing the bars 39 to the position illustrated in Figure 2 of the drawings. A coil spring 52 has one end anchored to the frame 37 and its other end 55

connected to the free end portion of the lever 48 for yieldingly urging the lever in a direction opposite to the direction in which said lever is moved by the chain 51. It may be 5 well to here state that the bars 39 are operatively connected by any suitable means such as chain or rope (not shown) to the locomotive whistle. Coiled springs 53 are connected to one end of each of the rods 27 for yielding- 10 ly retaining the frame carried whistle operating mechanism in inoperative position and for returning said mechanism in operative position after the whistle has been sounded.

Pairs of slotted cross beams 54 and 55 extend transversely between the railroad rails 56, said pairs 54 and 55 being disposed at longitudinally spaced points with respect to each other on the rails. All of the beams 54 and 55 are identical with each other in construction and a detailed description of one will, therefore, suffice for all. Each of said beams comprises a longitudinally slotted body portion having its end portions secured to the lower side of each of the rails 56 by 25 the U-bolts 57 having the rail flange engaging plates 58 secured thereon by the nuts 59. It is understood, of course, that the end portions of the beams through which the arms of the U-bolts 57 extend are unslotted and 30 are provided with apertures for the passage of the U-bolts.

A flat, metallic base plate 60 is supported on the beams 54 in parallel relation to the rails 56 and adapted for lateral adjustment 35 through the medium of the threaded bolts or shanks 61 which depend from the lower side of the base plate 60 and extend through the slots in the beams 54. Nuts 62 are threaded on the shanks 61 for frictionally securing 40 the base plate 60 in adjusted position on the beams 54. Upstanding brackets 63 are mounted on the opposite side portions of the base plate 60 and pivotally mounted for swinging movement in a vertical plane on the 45 inner side of each of the brackets 63 and at the upper end portion thereof is an arcuate plate 64. The arcuate plates 64 have extending therebetween the rods 65, 66, 67 and 68. Tubular metallic sleeves 69 and 70 are 50 mounted on the rods 65 and 68, respectively, between the arcuate plates 64. A pair of upstanding lugs 70 are provided on the base plate 60 and to which one end of each of the springs 71 is connected, the other ends of the 55 springs 71 being connected to intermediate portions of the rods 66 and 67. One end portion of the base plate 60 is longitudinally slotted and mounted for rotation in said slot is a pulley wheel 72. A bracket 73 depends 60 from one end of the base plate 60 and has connected thereto a tubular flexible cable housing 74. A flexible cable 75 of suitable material passes through the conduit or housing 74 and is trained under the pulley wheel 72 and has one end secured to the rod 66 be-

tween the collars 76 which are fixed on said rod 66.

As many pairs of the beams 55 may be provided at longitudinally spaced points on the rails 56 as may be desired and mounted between each pair of the beams 55 is what will be hereinafter referred to as a whistle operating unit which is designated generally by the reference numeral 76. Only one of the units 76 is illustrated in the drawings forming a part of this application. Each of the units 76 comprises a flat, horizontally disposed base plate 77 which is mounted for lateral adjustment on the beams 55 through the medium of the threaded shanks 78 which are operable in the slots of the beams 55 in a manner similar to the shanks 61 which secure the base plate 60 to the beams 54. Upstanding brackets 79 are rigidly mounted on the opposite longitudinal side edges of the base plate 77 and pivotally mounted for swinging movement in a vertical plane on the inner side of each of the brackets 79 and on the upper end portions of said brackets is a flat, metallic bar 80 having an integral leg 81 on one end portion thereof for engagement with the base plate 77 for limiting the swinging movement of the bar 80 in one direction and supporting the same in a horizontal plane when in inoperative position. The other end of each of the bars 80 is adapted 85 for abutting engagement with the base plate 77 for limiting the swinging movement of said bars 80 in the other direction and vertically disposed when in operative position. The rods 82 and 83 extend between the bars 80 and a tubular metallic sleeve 84 is mounted on the rod 82 between the bars 80. The opposite end portions of the base plate 77 are longitudinally slotted and journaled in said 90 slots are the pulley wheels 85. Brackets 86 depend from the ends of the base plate 77 and connected to one of said brackets is the other end of a flexible conduit or housing 74 which is connected to the base plate 60. All 95 of the units 76 which may be used or connected together by the flexible housings or conduits 88, one of which is shown connected to the end of the base plate 77 which is remote from the end of said plate to which the conduit 74 is connected. The flexible cable 100 105 110 115 120 125 130 75 is connected to an intermediate portion of the rod 83 of the unit 76. The cable 75 may be secured in any suitable manner to the rod 83 and the unit 76, and when more than one of the units 76 are used, the cable passes beneath the other of the rollers 85 and extends through the flexible conduits 88 to the next unit. The cable 75 is adapted to swing the bars 80 with the rods 82 and 83 from the position illustrated in full lines in Figure 8 of the drawings to the position illustrated in broken lines. A coil spring 89 has one end anchored to the base plate 77 and its other end connected to an intermediate portion of

the rod 83 in a manner to yieldingly urge said rod to vertical or operative position when the cable 75 is slackened. The coil spring 89 is enclosed in a suitable telescopic casing 90. Suitable supporting units 91 are 5 interposed in the conduits 74 and 88 between the various units for eliminating slack from said conduits. The units 91 may comprise a housing to the opposite sides of which the 10 conduits 74 and 88 are attached in any suitable manner, the cable 75 extending slidably through said housings. The unit or units 15 76 are disposed out of longitudinal alignment with the train actuated device which is operatively connected with said units 76.

The train actuating unit is designated generally by the reference numeral 92.

In operation, the unit 92 is disposed in the position illustrated in Figure 5 of the drawings. Should a locomotive or train be unintentionally switched on to the track equipped with this apparatus, and be traveling in the wrong direction over said track, the striker plate 10 engages with the rotary 25 tubular sleeve 69 on the rod 65 and swings the arcuate plates 64 from the position illustrated in full lines in Figure 5 of the drawings to the position illustrated in broken lines in said Figure 9. As will be apparent, 30 this movement of the plates 64 will pay out the cable 75 through the conduits 74 and permit the spring 89 to swing the bars 80 upwardly to vertical position from the horizontal position illustrated in broken lines 35 in Figure 8 of the drawings. In this position the tubular rotary sleeve 84 is disposed in the path of the depending finger 29 on the rods 27. When the finger 29 engages the tubular sleeve 84 and rides thereover, said 40 finger 29 is swung rearwardly and actuates the arm 30 through the rods 27. The arm 30, in turn, operates the lever 31 through the medium of the link 32 and the lever 31, through the medium chain 51, actuates the 45 lever 48 against the tension of the spring 52 in a manner to disengage the rod 45 from the plate 44 and permit actuation of the bars 39 by the coil spring 47. In this manner the whistle of the locomotive is sounded 50 to warn the engineer to bring the locomotive to a stop. The locomotive is then reversed to get off of the undesired track and when traveling in the other direction, the striker plate 10 engages the rotary tubular sleeve 55 70 on the rod 68 between the arcuate plates 64 and returns said plates to their initial or inoperative position. In this manner the bars 80 of the unit 76 are swung downwardly to their horizontal inoperative position by 60 the cable 75 and against the pull of the spring 89. The apparatus is then ready for operation again. It is understood, of course, that the bars 39 may be reset manually against the tension of the coil spring 47.

65 The track apparatus is preferably located

adjacent one end of a switch which enters the track and over which switch the locomotive which actuates the track units has, by mistake traveled in getting on to the wrong track. As the bars 80 of one of the 70 units 76 move to operative position, the next units 76 are permitted to successively move to operative position by the cable 75. Should a locomotive be coming in the opposite direction on the track before the locomotive 75 which is traveling in the wrong direction on the track has had an opportunity to get off of the track, the finger 29 of the last named locomotive will be actuated by the units 76 to sound the whistle on said last named locomotive to warn the engineer or operator to bring the same to a stop. The last named locomotive will, of course, contact with the unit 76 which is remote from the unit 92 first. The striker plate 10 may be adjusted 85 laterally on the supporting structure or frame 1 to engage with the unit 92 regardless of the position of said unit 92 on the beams 54 through the medium of the screw shaft 17, gears 18 and 19, the vertical rotary shaft 90 20 and the hand wheel 23. Through this means the striker plate 10 may also be disposed in a position to avoid the unit 92 when, for any reason, it may be desired to render the apparatus inoperative.

95 It is believed that the many advantages of a railroad safety device constructed in accordance with this invention will be readily understood, and although the preferred embodiment of the invention is as illustrated 100 and described, it is to be understood that changes in the details of construction may be had which will fall within the scope of the invention as claimed.

105 What is claimed is:—

1. A railroad safety apparatus of the character described comprising, in combination, a supporting structure to be mounted on a railroad locomotive, a finger pivotally mounted on the supporting structure and depending therefrom, means operatively connecting the whistle of the locomotive to the finger for actuation by said finger, a pair of spaced bars pivotally mounted for swinging movement in a vertical plane on the railroad track, a rod extending between the bars for swinging movement therewith into and out of the path of the finger for engagement by said finger in a manner to actuate the same, a pair 115 of plates pivotally mounted intermediate said ends for swinging movement in a vertical plane on the railroad track in spaced relation to the bars, rods extending between the end portions of the plates, and a striker plate mounted on the supporting structure and engageable with the last named rod in a manner to swing the plates in opposite directions, and a flexible cable operatively connecting the plates to the bars for actuating 120 125 130

the said bars in a manner to dispose the first named rods in the path of the finger.

2. A railroad safety apparatus of the character described comprising, in combination, a supporting structure to be mounted on a railroad locomotive, a finger pivotally mounted on the supporting structure and depending therefrom, means operatively connecting the whistle of the locomotive to the finger for actuation by said finger, a pair of spaced bars pivotally mounted for swinging movement in a vertical plane on the railroad track, a rod extending between the bars for swinging movement therewith into and out of the path of the finger for engagement by said finger in a manner to actuate the same, a pair of plates pivotally mounted intermediate said ends for swinging movement in a vertical plane on the railroad track in spaced relation to the bars, rods extending between the end portions of the plates, and a striker plate mounted on the supporting structure and engageable with the last named rod in a manner to swing the plates in opposite directions, and a flexible cable operatively connecting the plates to the bars for actuating the said bars in a manner to dispose the first named rod in the path of the finger, and resilient means operatively connected to the bars for swinging said bars in the other direction.

3. A railroad safety apparatus of the class described comprising, in combination, a supporting structure to be mounted on a railroad locomotive, a finger pivotally mounted on the supporting structure and depending therefrom, means operatively connecting the whistle of the locomotive to the finger for actuation by said finger, a pair of base plates mounted at longitudinally spaced points on the railroad track, upstanding brackets on each of the base plates, spaced, opposed bars mounted for swinging movement in a vertical plane on the brackets of one of the base plates, a rod extending between the bars and rigidly secured thereto and adapted for swinging movement therewith into and out of the path of the finger, said rod adapted to actuate said finger when engaged thereby, resilient means connected to the bars for swinging said bars to operative position, a pair of plates mounted for swinging movement on the brackets of the other base plates, a rod extending between the end portions of the last named plates, a striker plate mounted on the supporting structure and engageable with the last named rod for actuating the second named plates, and a cable operatively connecting the second named plates with the bars for swinging said bars and the first named rods to inoperative position out of the path of the finger, means for supporting the base plates for lateral adjustment between the rails of the railroad track, and means for mounting the pressure plates for lateral adjustment on the supporting structure.

supporting structure, and depending therefrom, means operatively connecting the whistle of the locomotive to the finger for actuation by said finger, a pair of base plates mounted at longitudinally spaced points on the railroad track, upstanding brackets on each of the base plates, spaced, opposed bars mounted for swinging movement in a vertical plane on the brackets of one of the base plates, a rod extending between the bars and rigidly secured thereto and adapted for swinging movement therewith into and out of the path of the finger, said rod adapted to actuate said finger when engaged thereby, resilient means connected to the bars for swinging said bars to operative position, a pair of plates mounted for swinging movement on the brackets of the other base plates, a rod extending between the end portions of the last named plates, a striker plate mounted on the supporting structure and engageable with the last named rod for actuating the second named plates, and a cable operatively connecting the second named plates with the bars for swinging said bars and the first named rods to inoperative position out of the path of the finger, means for supporting the base plates for lateral adjustment between the rails of the railroad track, and means for mounting the pressure plates for lateral adjustment on the supporting structure.

In testimony whereof I affix my signature.
SILVIO DRUDI.

4. A railroad safety apparatus of the class described comprising, in combination, a supporting structure to be mounted on a railroad locomotive, a finger pivotally mounted on the
